UNITED STATES PATENT OFFICE.

FREDERICK STINDT, OF LYNDHURST, NEW JERSEY, ASSIGNEE TO S. S. HEPWORTH COMPANY, OF NEW YORK, N. Y., A CORPORATION OF NEW YORK.

CENTRIFUGAL MACHINE.

Application filed June 3, 1925. Serial No. 34,643.

My invention relates to centrifugal machines, and particularly to an improved valve construction for open bottom baskets. The object of my invention is to provide a 5 valve which may be readily assembled or removed from position without disturbing the connection between the shaft and basket, or between the shaft and its driver.

In the accompanying drawing—
10 Fig. 1 is a broken side elevation of a centrifugal basket and casing showing my improved valve in position;

Fig. 2 is an enlarged broken plan view of the valve alone;

15 Fig. 3 is a plan view of the detachable segment of the valve handling member; and

Figs. 4 and 5 are respectively sections on the lines 4—4 and 5—5, Fig. 2.

A centrifugal basket of the type to which 20 my invention relates is suspended at the lower end of a driving shaft 15 attached to the basket bottom 16 by its central hub 17. The hub is connected by ribs 18 to the body of the casting to afford a central discharge 25 opening for the basket, while the shaft 15 is secured to the hub 17 by suitable machine screws or bolts 19 which take into the coned lower end 20 of the shaft.

To close the discharge opening during the 20 feed of wet material, such as molasses, to the interior of the basket, a valve disc is commonly provided which surrounds the spindle 15 and may be lifted upward on the latter to permit the discharge of the dried material, 35 such as sugar, from the basket. Ordinarily the valve is in the form of a one-piece casting, which is placed upon the spindle before the latter is secured to the basket bottom 16. To replace such a valve it is necessary to dis- 40 connect the spindle from the basket, or alternatively to disconnect the spindle from its top drive, and slip the new valve upon the shaft, after which the connections must be reestablished. Either operation is time con- 45 suming and difficult.

By my invention I have provided a valve 50 which may be readily placed upon the shaft without disturbing either the shaft connection to the basket bottom or to its drive. In the form shown the valve comprises a sheet metal disc 21 centrally apertured to fit the cone 20 at the foot of the spindle, and split transversely at 22 so that its ends 23 and 24 may be warped or spread as indicated in dotted lines, Fig. 1, to pass the

spindle 15 into or from the central opening 25 of the valve disc.

Associated with the valve disc proper and secured to its upper face, is a handle or lifting member. This is preferably in the form 60 of a two-piece casting, of which the segment 26 which cooperates with the segment 27 to form a complete annulus, has an arcuate extent sufficient to afford between the ends 28 and 29 of the casting 27 a space sufficient to 65 accommodate the shaft 15. Thus, after the valve plate has been passed upon the spindle 15, the segment 27 of the handle may be 70 passed transversely upon the spindle and secured to the valve plate 21. Thereafter the segment 26 may be fitted between the ends 28 and 29 of the segment 27, and also secured to the valve plate 21.

The valve handle is provided with an up- 75 turned lip 30 sufficiently spaced from the coned end of the spindle 15 to receive the end of a lifting hook, such as commonly used for removing the valve from closure position. The wall of the channel formed by the lip 30 is appropriately apertured at 80 31 to permit the escape of liquid therefrom.

The base of the handle is riveted to the 85 valve plate 21 at appropriate points 32, and is also preferably provided with a lug 33 which overlies the split 22 in the valve plate 21. This lug is riveted at 34 to both ends 23 and 24 of the valve plate and secures the ends firmly together in register. The segment 26 is also provided with a lip 35, which 90 registers with the lip 30, and its base is riveted at 36 to the valve plate in like manner. It is also provided with a lug 37 dia- 95 metrically opposite the lug 33 (to balance the latter) and provided with a like number of rivets in order that the structure may be symmetrical around the axis of the shaft.

When a valve unit of the present type be- 100 comes defective it is merely necessary to lift it on the shaft 15 to a convenient point, for example above the top of the basket casing 38, where it may be rested upon a couple of planks temporarily spaced across the casing on opposite ends of the shaft. The rivets which hold the handle and valve plate together may then be sheared and the valve 105 removed. The new valve plate and handle parts are passed transversely upon the spindle and riveted together, the planks removed and the valve unit lowered to position in the basket.

Various modifications in details of construction will readily occur to those dealing with the matter, which do not depart from what I claim as my invention.

5 I claim as my invention—

1. A valve for use with a centrifugal basket having a central bottom suspension surrounded by a discharge opening, said valve comprising a split valve plate adapted to be passed transversely onto the suspension shaft, and means for uniting the split ends of the valve plate to maintain them in register.

15 2. A valve for use with a centrifugal basket having a central bottom suspension surrounded by a discharge opening, said valve comprising a split valve plate adapted to be passed transversely onto the suspension shaft, together with valve handling means secured to said plate and serving to secure the split ends of the plate in register.

20 3. A valve for use with a centrifugal basket having a central bottom suspension surrounded by a discharge opening, said valve comprising a split valve plate adapted to be passed transversely onto the suspen-

sion shaft, together with a split annulus embracing the shaft and constituting valve handling means secured to said plate and serving to hold its ends in register.

25 4. A valve for use with a centrifugal basket having a central bottom suspension surrounded by a discharge opening, said valve comprising a split valve plate adapted to be passed transversely onto the suspension shaft, together with a balanced handling member adapted to overlie and be secured to said valve plate and to hold its split ends in register.

35 5. A valve unit for use with a centrifugal basket having a central bottom suspension surrounded by a discharge opening, said valve unit comprising a pair of split members adapted to embrace the shaft and be secured together, the split areas of said members lying on opposite sides of the shaft in assembled position, one of said members constituting a valve plate and the other member constituting a valve handling device.

40 In testimony whereof I have signed my name to this specification.

FREDERICK STINDT.
